UNITED STATES PATENT OFFICE

169,943

GASOLINE ENGINE

Arthur W. Mall, Flossmoor, and Odin Lingle, Chicago, Ill., assignors to Mall Tool Company, Chicago, Ill., a corporation of Illinois

Application March 18, 1953, Serial No. 24,086

Term of patent 14 years

(CL. D77—1)

To all whom it may concern:

Be it known that we, Arthur W. Mall and Odin Lingle, citizens of the United States and residing at Flossmoor, State of Illinois, and at Chicago, State of Illinois, respectively, have invented a new, original, and ornamental Design for a Gasoline Engine, of which the following is a specification, reference being had to the accompanying drawings, forming a part hereof.

Fig. 1 is a perspective view of a gasoline engine, showing our new design.

Fig. 2 is a perspective view taken from the right of Fig. 1.

Fig. 3 is a perspective view taken from a position diametrically opposite the view shown in Fig. 1.

We claim:

The ornamental design for a gasoline engine, substantially as shown.

ARTHUR W. MALL.
ODIN LINGLE.
